MARKER FOR ATHLETIC FIELDS

Wesley A. Kuoksa, Grand Rapids, Minn.

Application September 12, 1947, Serial No. 773,716

2 Claims. (Cl. 273—1)

1

My invention relates to markers for athletic fields, and the like, and also to a tool for inserting and removing such markers.

An important object of the invention is to provide markers which may be used to establish the boundary lines of an athletic field, such as a football field; the markers being of a permanent character, which cannot be obliterated by rain, or by being stepped on.

A further object is to provide a marker for athletic fields, which is designed to prevent injury to the players who may fall upon the same.

A further object is to provide markers which are inserted into the ground, and to provide means in the form of a tool to insert and remove the markers with a minimum of difficulty.

A still further object is to provide markers capable of forming a distinct visible line or boundary, said markers as well as the tool employed to insert and remove them being of simple and inexpensive design.

Other objects and advantages of the invention will be apparent during the course of the following description.

In the accompanying drawings, forming a part of this application, and in which like numerals are employed to designate like parts throughout the same,

Figure 1 is a plan view of a marker before the same is inserted into the ground.

Figure 2 is an enlarged vertical section on line 2—2 of Figure 1, and illustrating the position of the bottom end of an inserting tool, before the same drives the marker into the soil.

Figure 3 is a side elevation of a marker inserting and removing tool, and marker, and showing the same in their relative positions after the marker is inserted into the soil, but before the tool is removed, and

Figure 4 is a view showing markers which have been driven into the soil, and form part of a boundary line.

In the drawings, where for the purpose of illustration is shown a preferred embodiment of the invention, the numeral 6 designates the surface of an athletic field, or the like, having grass 7 growing thereon. The numeral 8, in Figure 4, designates markers which have been inserted or driven into the soil, and have their tops substantially flush with the top of the grass, to form a boundary line, or the like, upon the field. The markers may be placed about one foot apart, or as desired.

Each marker 8 includes a conical pointed foot or base 9, formed of any suitable material such

2

as wood or hard rubber. The top flat surface 10 of the base 9 has disposed upon it the inner ends of a plurality of spaced radial flexible strips or tapes 11, preferably formed of soft white rubber. Each radial strip 11 is preferably about ten inches in length from the base 9. The strips 11 are preferably joined or integral at their inner ends, to form a central portion or disc 12. A flat washer 13 is mounted upon the central portion 12 of the strips, and is secured in place, in tight clamping engagement upon the strips by means of an eye screw 14. The washer and central portion 13 are provided with center openings to receive the eye screw 14. When the markers are inserted in the soil, the strips 11 assume their positions shown in Figure 4, and the portions of the strips which extend above the surface 6 have enough rigidity to stand upright, and provide the necessary white spot, forming a part of the field boundary line.

A tool 15 for inserting and removing the markers 8 is provided. This tool includes a vertical tubular cylindrical member or bar 16, open at its bottom end, to engage over the washer 13 and eye screw 14, as best shown in Figure 2. The top of the bar 16 carries a hook 17, to engage in the eye screw 14 for pulling the markers 8 out of the ground. A combined foot bar and handle 18 is provided near the bottom end of the bar 16, and this foot bar is at right angles to the bar 16.

When the tool 15 is used to insert a marker 8, the bottom end of the bar 16 is placed over the washer 13 and eye screw, as shown in Figures 2 and 3. The strips 11 are beneath the lower edge of the tool and rest upon the surface of the ground. The tool is pressed downwardly by placing a foot upon the bar 18 and guiding the bar 16 with the hands. When the bar 18 engages the ground surface 6, the markers are inserted to the proper depth, and the tool 15 is removed.

If it is desired to remove the markers from the ground, the bar 18 is used as a handle and the top of the bar 16, carrying the hook 17 is inserted between the upstanding strips 11. The hook 17 is engaged into the eye screw 14, and the marker may be readily pulled up.

It is to be understood that the form of my invention herewith shown and described, is to be taken as a preferred example of the same, and that various changes in the shape, size and arrangement of parts may be resorted to, without departing from the spirit of my invention, or the scope of the subjoined claims.

Having thus described the invention, what I claim is:

1. A marker for athletic fields, comprising a base, adapted for insertion into the soil, substantially flexible strips mounted upon the base and adapted to assure upright positions when inserted into the soil, and means to attach the strips to the base.

2. A marker for athletic fields, comprising a pointed base to be inserted into the soil, substantially flexible radial strips disposed upon the base, a washer mounted upon the strips above the base, and an eye member connected with the base and serving to clamp the washer upon the strips.

WESLEY A. KUOKSA.
